UNITED STATES PATENT OFFICE.

GEORGES EDOUARD GRIMMEISEN, OF PARIS, FRANCE.

HYDROCARBON BURNER.

Application filed October 24, 1922. Serial No. 596,681.

To all whom it may concern:

Be it known that I, GEORGES EDOUARD GRIMMEISEN, a citizen of France, and a resident of Paris, France, have invented new and useful Improvements in Hydrocarbon Burners, of which the following is a specification.

This invention relates to improvements in hydrocarbon burners, the object of the invention being to provide an improved burner of this class embodying means for cracking the liquid hydrocarbon and to effect complete combustion thereof and thereby effect an economy in the use of the liquid hydrocarbon and also increase the illuminating power of the burner.

With the above and other objects in view, the invention consists in the construction, combination and arrangement of devices hereinafter described and claimed.

In the accompanying drawings

Figure 1 is a vertical central sectional view of a lamp burner constructed and arranged in accordance with my invention.

Figure 2 is a detail view, partly in elevation and partly in section of the cracking and diffusion plates and their supporting rod and adjusting means.

In the embodiment of my invention, I provide a pair of tubular wick tubes 1 and 2, one of unequal diameter, which are arranged one within the other and concentrically thereto to provide space for the tubular wick which is of the usual form. The inner wick tube forms a conduit for air. A concavo-convex cracking plate 2' is arranged above the upper end of the wick, with its concave side lowermost and is provided with an opening, as shown, for the passage of air therethrough and also for the passage of disassociated hydrocarbons. A suitable distance above the cracking plate 2 is a concavo-convex diffusion plate 3 which is also arranged with its concave side lowermost. Said diffusion plate is secured at the upper end of a vertical supporting rod 6 and said cracking plate is adjustably secured on the upper, threaded portion of said rod by means of nuts 7 so that the cracking plate may be arranged at any required distance from and below the diffusion plate.

A chimney 4 of any suitable form is mounted on a base or gallery 4' and in the lower end of the chimney is arranged a substantially truncated conical diaphragm 5 for the regulation of the air of combustion

which passes up around the exterior of the outer wick tube.

The operation of my improved burner is as follows. When the wick is lighted a flame is generated which heats the cracking plate 2 and causes a draft of air up through the chimney and also up through the interior wick tube as indicated by the arrows in Figure 1.

A part of the air introduces itself by the center of the wick and mixes with the vapors of dissociation resulting from the heating of the plate of cracking (primary air of the mixture, as in the ordinary Bunsen-burner).

An additional part of air enters thereupon through the space existing between the plate of diffusion 3 and the diaphragm 5, this complementary air being necessary for the complete combustion of the dissociated hydrocarbons and for the oxidation of the carbon, as in the ordinary Bunsen-burner.

Thereby a flame is produced, identical with that of a Bunsen-burner and comprising:

1. An obscure center at *a*,
2. A blue, pale shell at *b*, and
3. A very hot and very oxidizing point, of violet color, at *c*.
4. A base of the flame at *d*, the least heated part.

In the same way, as in a bunsen, it is necessary to regulate the proportions of air and of gas. It is also necessary to regulate the quantity of the air mixing with the hydrocarbons dissociated upon the plate of cracking. For this purpose the distance existing between the diffusion plate 3 on the one hand, and the cracking plate 2' on the other, may be increased or reduced by appropriately adjusting the nuts 7 on the rod 6, as will be understood.

In order to secure the heating of the cracking plate to the required constant temperature, this plate is maintained a suitable distance from the wick, so that the flame continues to maintain equally the cracking plate at the required temperature during the operation of the device.

What I claim, is:

1. A hydrocarbon burner comprising inner and outer wick tubes, a tubular wick arranged between the wick tubes, the said inner wick tube being also a conduit for air, a concavo-convex cracking plate arranged with its concave side lowermost and above

- and heated by the flame of the wick to dis-
associate the hydrocarburets and provided
with an opening therethrough for the pas-
sage of air and such disassociated hydro-
carburets, and a concavo-convex diffuser
plate arranged with its concave side lower-
most and above and in spaced relation to the
cracking plate and providing a mixing
chamber therebetween.
- 10 2. A hydrocarbon burner comprising in-
ner and outer wick tubes, a tubular wick ar-
ranged between the wick tubes, the said in-
ner wick tube being also a conduit for air,
a concavo-convex cracking plate arranged
15 with its concave side lowermost and above
and heated by the flame of the wick to dis-
associate the hydrocarburets and provided
with an opening therethrough for the pas-
sage of air and such disassociated hydro-
carburets, and a concavo-convex diffuser
plate arranged with its concave side lower-
most and above and in spaced relation to the
cracking plate and providing a mixing
chamber therebetween, a chimney around
20 and in spaced relation to the cracking plate
and diffuser, means to admit air to the lower
end of said chimney and a diaphragm in the
base of the chimney, open at its lower and
upper ends and presenting an upwardly and
inwardly inclined converging wall around
25 and in spaced relation to the cracking plate
and diffuser to supply complementary air
to the mixture.
3. A hydrocarbon burner comprising in-
ner and outer wick tubes, a tubular wick ar-
ranged between the wick tubes, the said in-
ner wick tube being also a conduit for air,
a cracking plate arranged above and heated
30 by the flame of the wick to disassociate the
hydrocarburets and provided with an open-
ing therethrough for the passage of air
and such disassociated hydrocarburets, and
a diffuser plate arranged above and in
35 spaced relation to the cracking plate and
providing a mixing chamber therebetween,
supporting means for the cracking plate and
diffuser and including means to permit the
relative adjustment of the cracking plate
40 and diffuser towards and from each other
to vary the width of the space between them
45 as required.
- 25 26 27 28 29 30 31 32 33 34 35 36 37 38 39 40 41 42 43 44 45 46 47 48 49 50
- In witness whereof I affix my signature.

GEORGES EDOUARD GRIMMEISEN.
